Frank C. Roberts

UNITED STATES PATENT OFFICE.

FRANK C. ROBERTS, OF PHILADELPHIA, PENNSYLVANIA.

HOT-BLAST STOVE.

SPECIFICATION forming part of Letters Patent No. 642,924, dated February 6, 1900.

Application filed November 7, 1899. Serial No. 736,091. (No model.)

To all whom it may concern:

Be it known that I, FRANK C. ROBERTS, a citizen of the United States, residing at Philadelphia, in the county of Philadelphia, State 5 of Pennsylvania, have invented a new and useful Improvement in Hot-Blast Stoves, of which the following, taken in connection with the accompanying drawings, is a full and clear specification.

10 My invention relates to improvements in hot-blast stoves whereby the loss of heat by radiation is reduced and at the same time a more thorough combustion of the gases secured.

15 Figure 1 is a vertical section through a hot-blast stove; Fig. 2, a horizontal section on line A B, (see Fig. 1,) and Fig. 3 a horizontal section on line C D. (See Fig. 1.)

Similar letters refer to similar parts throughout the several views.

As ordinarily constructed fire-brick stoves of the type illustrated are built with a solid wall between the combustion-chamber and the outside of the stove. As this wall becomes 25 hot by the burning of gas in the combustion-chamber there is a certain amount of heat lost through the wall by radiation, &c. Again, as ordinarily constructed air for the combustion of gas is admitted in the vicinity of the 30 gas connection to the stove, and while the combustion is good under these circumstances yet it is much better when the air admitted is heated.

The objects of my invention are (a) to prevent the loss of heat referred to above and (b) to heat a portion of the air for the combustion of the gases and deliver it into the combustion-chamber at a desirable point.

The drawings illustrate a fire-brick stove, 40 wherein N is the metal shell; E, the combustion-chamber; F, the checker-work, supported by piers G; H and I, walls around the combustion-chamber, between which is space J, open at bottom to atmosphere by openings K, controlled by valves, and open at top to combustion-chamber by openings L.

The operation of my invention is as follows: Gas is admitted through the opening M, controlled by a valve. This gas is partially con- 45 sumed by the admission of air in the vicinity

of M, the quantity of air being controlled by a gate or other type of valve. The products of combustion pass upward through E, downward through F, and out of the stove by the chimney connection O. Air is also admitted 55 through openings K to space J and in passing upward absorbs the heat passing through wall H, being finally delivered in a heated state into the combustion-chamber E through openings L, where it comes in contact with the partially-consumed gases and contributes toward their thorough combustion. By the above-described process the exterior wall I is prevented from reaching a high temperature, and thus the loss of heat is prevented, while the 60 heat which would otherwise be wasted is delivered at the top of the combustion-chamber. 65

The type of stove shown in the drawings is known as a "two-pass" stove, having its combustion-chamber next the outer walls. A 70 stove may be either two-pass, three-pass, or any number of passes and yet have the combustion-chamber located next the outer walls, as shown in the drawings.

I do not limit my invention to the type of 75 stove shown in the drawings. It may be applied to any type of stove, provided only that the combustion-chamber is located next the outer walls in distinction from a stove in which the combustion-chamber is surrounded 80 on all sides by checker-work.

Having fully described my invention, what I claim, and desire to cover by Letters Patent, is—

In a hot-blast stove having its combustion-chamber located next the outer walls, the combination of a combustion-chamber, two walls between the combustion-chamber and the external metal shell, an air-space between said two walls, openings controlled by valves or other devices leading from the atmosphere 85 into said air-space and openings from said air-space into the combustion-chamber. 90

In testimony whereof I have hereunto set my hand this 4th day of November, 1899.

FRANK C. ROBERTS.
